*Inventor.
Charles J. Nauen*

By: Eric Spear Jr.
Attorney.

UNITED STATES PATENT OFFICE.

CHARLES J. NAUEN, OF WEST SOMERVILLE, MASSACHUSETTS.

LOOM.

Application filed September 17, 1923. Serial No. 663,041.

To all whom it may concern:

Be it known that I, CHARLES J. NAUEN, a citizen of the République of Germany, with first papers for naturalization in the United States, residing at West Somerville, county of Middlesex, Commonwealth of Massachusetts, have invented certain new and useful Improvements in Looms, of which the following is a specification.

10 My present invention relates to double fabric looms, but primarily to a loom for independent two piece weaving. The advantages of such weaving will be readily perceived by those skilled in the art. There is not only an obvious doubling of capacity with only a slight increase of attendance required, but in accordance with my invention such doubled production is obtained without increase in floor space or power required for

20 the ordinary single loom.

Moreover, my invention materially increases the convenience of operation and inspection, particularly the inspection of the fabric while being woven, in that the warps are disposed as adjacent vertical flights through which the light readily filters. Consequently, both pieces being woven may be constantly observed during the run of the loom and any imperfection in the fabric immediately noted.

As illustrative of my invention, I have shown in the accompanying drawings so much of a loom in accordance with my invention as will illustrate the principles involved and will enable those skilled in the art to understand its construction and operation. The parts not shown therein are standard parts and fixtures such as are employed in ordinary looms and it will be noted that while my loom is a type quite novel and distinct, it conforms to standard principles and permits the utilization of parts standardized to loom manufacture and wholly familiar to the usual loom operatives.

Utilizing the illustrated structure as a characteristic embodiment by which the nature of my invention may be understood, I will now proceed to a more detailed discussion of the principles involved therein, it being understood that such embodiment and discussion is illustrative rather than specific except where specific features of my invention are set forth as elements of novelty. Throughout the specification and drawings

like reference characters are employed to indicate corresponding parts, and in the drawings:

Fig. 1 is a front elevation of a double fabric, vertical flight, loom in accordance with my invention.

Fig. 2 is a side elevation thereof.

Fig. 3 is a detail view particularly illustrating the action of the heddles.

Fig. 4 is a partial plan view of one of the pairs of shuttle boxes, and also showing a portion of the reed mechanism.

Figs. 5 and 6 are sections on the lines 5—5 and 6—6, respectively of Fig. 1, and

Fig. 7 is a partial plan view of Fig. 1.

I have indicated at 1 the side frames of a loom in accordance with my invention. Journaled transversely across the lower end of the frames 1 at the front and rear thereof is a pair of oppositely disposed warp beams 2 from which the warp flights W are drawn to a pair of superposed cloth beams 3 journaled at front and rear of said frames 1 adjacent the upper ends thereof, guide rolls 4 and 5 being provided adjacent the warp and cloth beams for causing the warp flights to travel in straight lines vertically of the loom.

The cloth beams are rotated in unison from a clutch shaft 6 (Fig. 7) which is provided at 7 with a clutch and at 8 with a clutch shift lever and beyond said clutch has fast thereon a beveled gear 9 meshing with pinions 10 on a pair of worm shafts 11 which are provided at their outer ends with hand wheels 12 whereby either cloth beam may be independently adjusted. Each worm shaft 11 is provided with a worm 13 meshing with a worm wheel 14 on a stub shaft 15 (Fig. 1) which carries a pinion 16 meshing with a gear 17 fast on each cloth beam shaft.

Resting upon one of the cloth beams is an overlying roller 18. The roller 18 is carried at one end on an arm 19 which is connected by a stud 20 with a link 21. The link 21 is connected at 23 with an eccentric 32 fast on a crank shaft 31 journaled transversely of the loom, and said shaft is rotated by a gear 48 thereon meshing with a gear 49 on the power shaft 50 of the loom (Figs. 1 and 2).

The stud 20 works in a longitudinal slot 22 (Fig. 2) formed in a vertical pawl carrying lever 23 which is fulcrumed at its lower end on the shaft 24 of a ratchet wheel 25

and is provided with a plurality of relatively staggered feed pawls 26 adapted for intermittent engagement with the ratchet wheel according to the position of the pawl carrying lever. A similar series of relatively staggered holding pawls 27 is provided to prevent a back-lash of the ratchet wheel. Fast on the ratchet shaft 24 is a pinion 28 which through a gear train 29 and 30 drives the shaft 6.

At each revolution of the crank shaft 31 the pawl lever 23 is rocked on its pivot by the link 21, and through the engagement of the feed pawls 26 with the ratchet 25, said 15 ratchet is turned through a part of a revolution and by means of the gear train 28, 29, rotates the drive shaft 6 for the cloth beams 3. As the diameter of the cloth beam increases, the roll 18 is lifted by the successive 20 layers of cloth wound on the beam and by reason of its connection at 20 with the link 21 raises said link in the slot 22 of the pawl carrying lever 23, thus changing the leverage, and thereby automatically reducing the 25 number of picks.

Inasmuch as the loom of the present invention is designed to weave two independent lengths of fabric, it is necessary to employ two shuttles with appropriate picker 30 mechanism for operating the same, together with suitable heddle and reed mechanism operating in properly timed relation to the 35 flight of the shuttles. I have accordingly indicated at 34 a batten which extends transversely of the loom approximately midway of the height of the side frames 1 and which carries the shuttle boxes and the reed mechanism. The batten 34 is automatically raised and lowered to open and close the 40 shed by means of cranks 35 (Fig. 1) on the crank shaft 31 and connecting rods 35' to the batten, being guided in its vertical travel by guide rods 36 carried by the side frames 1. The shed is open when the cranks are 45 lowered (Fig. 1) and is closed when the cranks are raised.

The batten 34 has at either side thereof and spaced therefrom side strips 37 (Fig. 5) which define with the batten independent 50 parallel guideways 38 for the shuttles S. Beyond the side frames 1 the batten 34 has bolted thereto at 39 on either side thereof a pair of blocks 40 (Fig. 6) constituting the bottom surfaces of the shuttle boxes. The 55 side walls of the shuttle boxes are indicated at 41 and the blocks 40 are vertically slotted as indicated at 42 to admit the picker sticks 43 which are fulcrumed upon the side frames 1 at 44 and are actuated in the usual 60 manner.

Mounted upon the batten 34 is an overlying strip 45 which with other strips 46 overlying the guide walls 37 and spaced therefrom as indicated at 47, Fig. 5, constitute a mount for the reeds R past which the

shuttles travel. With my construction therefore, the reeds R rise and fall with the batten 34 as actuated from the crank shaft 31 whereby to open and close the shed at the proper moment during the flight of the 70 shuttles.

The warp W is opened and closed in properly timed relation to the movement of the batten by heddles H arranged beneath the batten and moved laterally relative 75 thereto by the usual dobby. Inasmuch as this dobby forms no part of my present invention, it is not illustrated, although the heddles are shown in Figs. 3 and 5.

In order to maintain a dragging tension 80 upon the warp beams, each beam roll is provided with a gear 52 meshing with a pinion 53 on a stub shaft 54, the ratio between the gears 52 and 53 being preferably a one to two ratio, and the stub shaft 54 carrying a 85 pulley 55 over which is suspended a counterweight 56, the free end of the cord which carries said counterweight being wrapped a few times around the pulley to secure it 90 thereon.

It will thus be seen that with my loom two 95 lengths of fabric are simultaneously woven in vertical flights, and that this method of weaving not only doubles the production of the loom without material increase in either floor space or power required, but permits convenient inspection of the fabrics for imperfections while they are being woven.

Various modifications in the construction 100 and operation of my device may obviously be resorted to without departing from the spirit of my invention, if within the limits of the appended claims.

What I therefore claim and desire to secure by Letters Patent is:

1. In a loom, a crank shaft having an eccentric thereon, a pair of cloth beams, a pawl carrying lever operated from said eccentric and having a pawl, a ratchet driven by said pawl, a common drive shaft for the cloth beams and operatively connected to said ratchet, and a regulating device in contact with the fabric being wound upon one of said cloth beams and operatively connected with the connections between said eccentric and said pawl carrying lever, whereby to change the effective leverage of said lever as the diameter of said cloth beam increases.

2. In a loom, a crank shaft having an eccentric thereon, a pair of cloth beams, a pawl carrying lever operated from said eccentric and having a plurality of relatively staggered pawls, a ratchet driven by said pawls, a common drive shaft for the cloth beams and operatively connected to said ratchet, a regulating roller in contact with the fabric being wound upon one of said cloth beams and operatively connected with the connections between said eccentric and

said pawl carrying lever, whereby to change the effective leverage of said lever as the diameter of said cloth beam increases.

3. In a loom, a crank shaft having an eccentric thereon, a pair of cloth beams, a pawl carrying lever operated from said eccentric and having a pawl, a ratchet driven by said pawl, a common drive shaft for the cloth beams and operatively connected to 5 said ratchet, worm shafts operated from said drive shaft, a clutch mechanism for selectively connecting said worm shafts, a

speed reduction gear train between said worm shafts and said cloth beams, and a regulating roller in contact with the fabric 15 being wound upon one of said cloth beams and operatively connected with the connections between said eccentric and said pawl carrying lever whereby to change the effective leverage of said lever as the diameter 20 of said cloth beam increases.

In testimony whereof I affix my signature.

CHARLES J. NAUEN.
